HARRY G. DAVIDSON, OF ORTEGA, FLORIDA

PROPELLION MEANS FOR BOATS

Application filed October 4, 1929. Serial No. 397,304.

My invention relates to improvements in propulsion means for boats, more particularly to propulsion means adapted to perform the steering operation, and it consists of the combinations, constructions, and arrangements herein described and claimed.

An object of my invention is to provide a simple mechanism of the so called "out board" type, which will transform a simple oscillatory movement, which may be imparted thereto by hand or other means producing a suitable movement, into the more complex movement, greatly used for boat propulsion and commonly called a sculling motion.

15 A further object of my invention is to provide a boat operating mechanism that supports the arm of the operator, and the weight of his body imposed thereon in an easy and comfortable fashion during the operation.

20 A further object of my invention is to provide such a mechanism as will be readily mountable on any boat of conventional form.

A further object of my invention is to provide a propulsion means, which, when mounted 25 for operation, can quickly and easily be shifted from a boat propulsion position in the water to a non-propulsion position out of the water.

30 A further object of my invention is to provide means for shifting the position of my boat propulsion means relative to the boat, for the purpose of steering said boat.

35 A further object of my invention is to provide a device of the type described which is simple in construction, has few parts, and is not likely to get out of order easily.

40 Other objects and advantages will appear in the following specification, and the novel features of the invention will be particularly pointed out in the appended claims.

45 My invention is illustrated in the accompanying drawings, forming part of this application, in which—

Figure 1 is a side elevational view of a device according to my invention, shown in operative position,

50 Figure 2 is a rear elevational view of a device according to my invention, with parts thereof being shown in section,

Figure 3 is a top plan view of the device shown in Figures 1 and 2,

Figure 4 is a sectional view on the line 4—4 of Figure 1,

Figure 5 is a sectional view on the line 5—5 of Figure 1,

Figure 6 is a perspective detail view of a portion of the device, and

Figure 7 is a sectional detail view on the line 7—7 of Figure 2.

In carrying out my invention I make use of a mounting frame 1 provided with an extended bifurcation, presenting the walls 1a and 1b for engagement with the top of the stern-board of a boat. The wall 1a is provided with screw-threaded apertures, through which the clamp members 1c and 1d, adjustably engage the stern-board, for securely fastening the mounting frame to said board.

This mounting frame is provided with two 70 upstanding journal-bearing portions 2 and 3, in which the mounting shaft 4 is non-rotatably journaled by means of the keys and keyways 5 therein. This mounting shaft is provided with the two longitudinally extending slots 6 and 7 for a purpose presently to be described.

Rotatably journaled on the mounting shaft 4 by the journals 8 and 9, is the supporting frame 10 providing the bearings for supporting the shafts 11, 12, and 13, from opposing points in the vertical walls of said frame. Fixedly related to the shaft 11 and adapted for rotation between the vertical walls of the frame 10 is the flywheel 14, which is provided 75 at the periphery thereof with a hollow tubular portion 15 filled with a liquid for the purpose of adding to the inertia thereof. Non-rotatably mounted relative to shaft 11 and adjacent the ends of said shaft are the pinion 80 gears 16 and 17 adapted for rotation on the outside of the vertical walls of the frame 10. These pinions engage and are rotated by the gears 18 and 19 rotatably mounted on the stub shafts 12 and 13 projecting outwardly 85 from each vertical wall of the supporting frame 10, and providing extended bearings for the bosses 18a, 19a of the gears 18 and 19 respectively.

These bosses are of a peculiar construction 90

having the extended portions 18b and 19b thereon essentially providing cranks, which are set 180° apart, for swivelly mounting the cooperating crankpins 18c and 19c thereon.

These crank pins are fixedly mounted in the sides 20 and 21 of the double yoked member 22.

The double yoke member upon which the propelling means proper 22a is mounted, is provided in the bottom portion thereof with an arcuately extending slot 23 for the accommodation of a stationarily mounted pin 24, fixed for the lower portion of the supporting frame 10, and slidably engaged in said arcuate slot. The top portion of this double yoke member is provided with a pin 25 fixedly related thereto and provided with a roller member 25a for engagement with a second 20 arcuately shaped slot 26 comprised in the operating lever 27 rotatably journaled at its center in the upper portion of the supporting frame 10 as indicated at 27a.

To impart an oscillating movement to this operating lever, I provide the actuating lever 28, fixedly related to the said operating lever at its center, and provided with a handle 28a for manually swinging said lever between the limits 29 and 30, prescribed therefor by the 30 arcuately extending guide slot 31 comprised in the upper fore portion of the supporting frame 10. This frame 10 is provided with enlarged walls 32, and 33 for the accommodation of lever 28.

For permitting the operator to rest his forearm in an easy manner during the operation, the arm rest and support 34 is provided. This arm rest is provided with a downwardly extending swivel pin as shown at 35, secured for turning and sliding movement by any suitable means in slot 36, extending longitudinally of frame 10. Pivotally mounted on this swivel pin 35 is the link 37, the other end of which is pivoted to the sliding guide bolt 38, and held thereon by any suitable means. This guide bolt 38 is swivelly and slidably mounted in guide slot 39. On the lower end of bolt 38 is pivotally secured the link 40, the other end of which is pivotally mounted on clamp pin 41, which is clamped to lever 28.

Pivotally mounted as indicated at 42a on the supporting frame 10 is the key-supporting frame 42 normally urged upwards relative to said frame by the spring means 42b fastened to the frame 10 as shown at 42c. Provided in the elbow of this key-supporting frame is the key 43, adapted to engage either one of the slots 6 or 7 in the mounting shaft 44. The key-supporting frame is further provided with portion 44 for a purpose soon to be described.

For the purpose of steering the boat I provide the front portion of the supporting frame 10 with a transversely extending rack

45, engaging the rack segment 46 as more clearly shown in Fig. 5. The rack 46 is pivoted for oscillatory movement on the mounting frame by the means shown at 47, and is further provided with the actuating lever 70 portion 48, providing handle 48a, for the purpose of permitting said rack segment to be manually oscillated about its pivot.

For maintaining the steering means in any desired position, the mounting frame provides a series of arcuately extending and vertically projecting lugs 49, between any two of which the actuating lever 48 may be placed and held from swinging movement, thereby mounting the rack 45 and attached frame 10, supporting the propulsion means, in fixed steering relation to the boat.

From the foregoing description of the various parts of the device, the operation thereof may be readily understood. The handle 28a is swung back and forth in its guide slot 31, imparting to the operating lever 27, an oscillatory movement about its pivot 27a. This movement of the lever 27, causes the pin 25 to slide back and forth in the slot 26, imparting to the yoke 22 a variable oscillation or figure of eight movement about the fixed fulcrum 24 engaged in the slot 23, said movement being made more "smooth" and continuous by the interposition of the flywheel 14 therein. This movement is more clearly understood by an examination of Fig. 2, wherein it is seen that one stroke of the actuating lever 27 will cause the crank pin 18c to move and rotate its wheel 18 in one direction while the pin 19c will be moved and rotates its wheel 19 in the same direction. This motion causes the double yoke 22 to turn about its longitudinal axis and slide to a vertical position by means of the pin and slot means. This motion imparted to the gears 18 and 19 operating through the pinions 16 and 17 imparts one full revolution to the flywheel 14, the momentum of which serves to continue the rotation of gears 18 and 19 whereby serving to aid in the reverse movement of the actuating lever and the movement of the double yoke 22 from said vertical position to horizontal position opposite to that shown in Fig. 2. It can readily be seen that an effective sculling or figure of eight motion will be imparted to the propulsion member 22a. During this operation, the arm of the operator is suitably supported at 34, as shown in Figure 3, the said support 34 reciprocating back and forth and swivelling in the slot 36, suitably guided and moved by its connection through link 37, bolt 38, link 40 and clamp pin 41, to lever 28, thereby preserving a constant distance between the handle 28a and said arm support 34, whereby sliding movement between the arm of the operator and the support 34 is prevented. It is also seen that this support 34 adds to the comfort of the operator by per-

mitting him to rest the weight of the upper portion of his body thereon.

When the operator desires to raise the apparatus from its propulsion position shown in Fig. 1 to non-propulsion position out of the water, it is merely necessary for him to depress the member 42 by means of the flat portion 44 thereon, thereby releasing the key 43 from the slot 6, raise the apparatus from the water pivotally on its shaft 4 and insert the key 43 in slot 7; thus securing the device in an inoperative position.

By oscillating the handle 48 the supporting frame 10, because of the engagement of rack 45 thereon with rack 46, is slid along the mounting shaft 4 to variably position the propulsion mechanism for steering means in a manner easily understood.

I claim:—

20 1. In a boat propulsion means, a propeller member, and means for actuating said propeller member, comprising an oscillating lever adapted for manual operation, an operating lever oscillated by said oscillating lever, a yoke member fixedly related to said propeller member and slidably related to said operating lever, crank means in offset relation, engaging the opposite sides of said yoke member, and a stationary pivot member slidably 25 related to said yoke member, whereby a sculling or figure eight motion is imparted to said propeller member.

2. In a boat propulsion means, a propeller member, and means for actuating said propeller member, comprising an oscillating lever adapted for manual operation, an operating lever oscillated by said oscillating lever, a yoke member fixedly related to said propeller member and slidably related to said operating lever, crank means in offset relation, engaging the opposite sides of said yoke member, an inertia member operatively connected with said crank means, and a stationary pivot member slidably related to said yoke member, whereby a sculling or figure eight motion is imparted to said propeller member.

3. In a boat propulsion means, a propeller member, and means for actuating said propeller member, comprising an oscillating lever adapted for manual operation, an operating lever oscillated by said oscillating lever, a yoke member fixedly related to said propeller member and slidably related to said operating lever, crank means in offset relation, engaging the opposite sides of said yoke member, an inertia member operatively connected with said crank means, said inertia member consisting of a wheel provided with 50 a hollow fluid-containing tire and a stationary pivot member slidably related to said yoke member, whereby a sculling or figure eight motion is imparted to said propeller member.

65 4. In a boat propulsion means, a propeller

member, and means for actuating said propeller member, comprising an oscillating lever adapted for manual operation, a stationary guide slot limiting the movement of said oscillating lever, an operating lever oscillated by said oscillating lever, a yoke member fixedly related to said propeller member and slidably related to said operating lever, crank means in offset relation, engaging the opposite sides of said yoke member, and a fixed stationary pivot member slidably related to said yoke member, whereby a sculling or figure eight motion is imparted to said propeller member.

5. In a boat propulsion means, a propeller member, and means for actuating said propeller member, comprising an oscillating lever adapted for manual operation, an operating lever oscillated by said oscillating lever, a yoke member fixedly related to said propeller member and slidably related to said operating lever, crank means in offset relation, engaging the opposite sides of said yoke member, said crank being positioned at an angle to their axis of rotation, and a fixed stationary pivot member slidably related to said yoke member, whereby a sculling or figure eight motion is imparted to said propeller member.

6. In a boat propulsion means, mechanism adapted to propel the boat, and means for variably positioning said propulsion mechanism relative to said boat, comprising an elongated shaft on which said propulsion mechanism is slidably mounted, and positioning mechanism for sliding said propulsion mechanism on said shaft, whereby the steering operation is performed.

7. In a boat propulsion means, mechanism adapted to propel the boat, and means for variably positioning said propulsion mechanism relative to said boat, comprising an elongated shaft on which said propulsion mechanism is slidably mounted, and positioning mechanism for sliding said propulsion mechanism on said shaft, consisting of a rack mounted on said propulsion mechanism, a cooperating rack segment oscillatably mounted relative to said shaft and adapted for manual operation, whereby the steering operation is performed.

8. In a boat propulsion means, mechanism adapted to propel the boat, and means for variably positioning said propulsion mechanism relative to said boat, comprising an elongated shaft on which said propulsion mechanism is slidably mounted, and positioning mechanism for sliding said propulsion mechanism on said shaft, consisting of a rack mounted on said propulsion mechanism, a cooperating rack segment oscillatably mounted relative to said shaft, and adapted for manual operation, and detent means for said holding rack segment from oscillating

movement, whereby the steering operation is performed.

9. In a boat propulsion means, a propeller member, and means for actuating said propeller member, comprising an oscillating lever, means for oscillating said lever, propeller member supporting means slidably related to said oscillating lever, a fixed guide member slidably related to said propeller member supporting means, and means engageable at points between said oscillating lever and said fixed guide member and on opposite sides of said propeller member supporting means for guiding said points in concentric paths of opposite phase, whereby a sculling motion is imparted to said propeller.

10. In a boat propulsion means, mechanism adapted to propel the boat, mounting means, comprising an elongated shaft, adapted to pivotally support said propulsion mechanism, and means for swinging said propulsion mechanism into operative and inoperative positions comprising portions of said shaft having slots, a key for engagement in said slots, and a lever mounted on said propulsion mechanism to support said key and aid in moving said mechanism to operative and inoperative positions.

11. In a boat propulsion means, mechanism adapted to propel the boat, mounting means, comprising an elongated shaft, adapted to pivotally support said propulsion mechanism, and means for swinging said propulsion mechanism into operative and inoperative positions comprising portions of said shaft having slots, a key for engagement in said slots, and a lever pivoted to said propulsion mechanism to support said key, said lever being so disposed relative to said shaft and said propulsion mechanism that the weight of said propulsion mechanism maintains said key in position in a desired slot.

12. In a boat propulsion means, a propeller member, and means for actuating said propeller member comprising an oscillating lever adapted for manual operation, a reciprocating arm rest, and a link interconnecting said lever and said arm rest.

13. In a boat propulsion means, a propeller member, means for actuating said propeller member comprising an oscillating hand lever, and a reciprocating arm rest connected to said lever to facilitate operation thereof by an operator.

14. In a boat propulsion means, a propeller member, means for actuating said propeller member comprising an oscillating hand lever, and a pivotally mounted reciprocating arm rest connected to said lever to facilitate operation thereof by an operator.

HARRY G. DAVIDSON.
